UNITED STATES PATENT OFFICE.

WILLIAM E. HARRIS, OF NEW YORK, N. Y.

OXIDIZING-FURNACE.

SPECIFICATION forming part of Letters Patent No. 276,175, dated April 24, 1883.

Application filed April 26, 1882. (No model.)

To all whom it may concern:

Be it known that I, WILLIAM EDWARD HARRIS, of the city, county, and State of New York, have invented a new and useful Improvement 5 in Oxidizing-Furnaces, of which the following is a full, clear, and exact description.

Reference is to be had to the accompanying drawings, forming part of this specification, in which similar letters of reference indicate corresponding parts in both the figures.

Figure 1 is a perspective view of my improvement, parts being broken away. Fig. 2 is a sectional side elevation of a part of the same.

15 The object of this invention is to facilitate and cheapen the operation of oxidizing ores.

The invention is embodied in the construction and combination of parts, as hereinafter described and claimed, whereby hot air and 20 the gaseous products of combustion taken from the ore-chamber and forced into the space beneath the ore-grate, and from which (it being otherwise closed) they are forced up through the tile-covered grate whereon the ore rests, a 25 continuous circulation being thus maintained through the ore until completely oxidized.

A represents the fire-chamber, B the fire-grate, and C the bridge-wall of the furnace.

D is the oxidizing-chamber, which is divided 30 into upper and lower compartments by a grate, E. Upon the grate E are laid tiles F, upon which the ore to be oxidized is spread to the depth of about a foot.

The ore is introduced into the chamber D through hoppers G, placed in openings in the 35 top of the furnace, and is spread evenly over the tiles F by means of a hoe, rake, or other tool introduced through doors H in the front of the said furnace. Steam is forced into the 40 lower compartment of the chamber D through a pipe, I. Hot air is drawn from the upper part of the chamber D, through a pipe, J, by a fan-blower or other suitable means, and is forced into the lower compartment of the said

chamber D through a pipe, K. The steam and 45 hot air rise through the grate E, the tiles F, and the ore spread upon the said tiles, so that the ore will be oxidized quickly and with a small amount of fire. The hot air that is not drawn through the pipe J passes over the top of 50 the division-wall L, passes down through the end chamber, M, which forms the mouth of the flue, and passes through the flue N in the lower part of the furnace to the stack O.

I am aware that steam has been introduced 55 beneath a grate and allowed to pass up through ore resting thereon, also that the gaseous products of combustion have been forced in a continuous current by means of a blower over a charge of ore, and returned in a 60 flue beneath it; but in these cases the object was rather to prevent than promote oxidation, since very little oxygen was allowed to enter the converting-chamber, so that the ore might be quickly reduced to a metallic state. 65 In my invention I combine a steam-conveying pipe and blower with a furnace and ore-grate in such manner that the steam and hot air and gaseous products of combustion are commingled and forced up through the charge 70 of ore, whereby the oxidation, rather than reduction, of the latter is produced.

Having thus fully described my invention, I claim as new and desire to secure by Letters Patent—

75 The combination of a fire place and grate with a roasting-chamber provided with a grate, E, and tiles F, covering the same, a flue-chamber, M, connected with the chimney, as described, a pipe for conveying steam below the 80 grate E, and pipes J and K, connected by a fan exhaust and blower, as and for the purposes described.

WILLIAM EDWARD HARRIS.
